UNITED STATES PATENT OFFICE.

HENRY F. SHAW, OF BOSTON, MASSACHUSETTS, ASSIGNOR TO FRANKLIN T. PRINCE, OF DORCHESTER, MASSACHUSETTS.

AUTOMATIC PRESS.

No. 806,370.

Specification of Letters Patent.

Patented Dec. 5, 1905.

Application filed March 9, 1905. Serial No. 249,212.

To all whom it may concern:

Be it known that I, HENRY F. SHAW, of Boston, in the county of Suffolk and State of Massachusetts, have invented certain new and useful Improvements in Automatic Presses, of which the following is a specification.

The object of this invention is to provide a self-acting press of simple, cheap, and effective construction adapted for various household purposes and operating without a pressure-screw, but by a peculiar leverage utilizing its own weight and that of the material being treated to produce an increasing pressure.

15 My invention embodies a horizontal base or body comprising or supporting the mold or pan with a cover or movable follower-plate and having at each end a short upright post or other fulcrum in combination with actuating-levers forming supporting-legs having a spreading action and so fulcrumed on said posts that the short arms of said levers press upon the follower-plate, while the much longer arms rest terminally on the floor or table. 20 These lower ends are broadened to form supporting-feet, and each has a roller to facilitate movement as the legs spread with compression of the material, thus increasing the leverage.

In the drawings, Figure 1 is a top plan of 30 my improved press, shown as in use. Fig. 2 is a vertical central section indicating position of parts as the material becomes somewhat compacted. Fig. 3 is a view in side elevation, showing the parts detached.

35 The numeral 5 represents a flat base, preferably an open-work casting formed with upright fulcrum-posts 6, extending obliquely outward. A suitably-shaped mold or pan 7, tapering somewhat downwardly, is adapted 40 to rest on the base 5 and is provided with a loose-fitting follower-plate 8, having a knob or handle 9. The material to be treated will be placed in the mold and covered by said plate. The mold or pan may be secured to or 45 made integral with the base, or, in other words, the base may have raised sides and ends with capacity to contain the material to be acted upon. It is, however, more convenient to have the pan removable, as shown in 50 Fig. 3.

To the top of posts 6 the actuating-levers are pivoted at such intermediate point as to give a leverage of about three to one. The short arms 10 of these levers are so shaped as

to bear transversely upon the upper surface 55 of the follower-plate during the whole period of pressure, and such long arm 11 extends downwardly and obliquely when in use and spreads at bottom to form a transverse foot of considerable breadth. Each foot is furnished with a terminal roller 12 to facilitate the spreading action when the press is in use. A similar roller 13 may be applied to the upper end of arm 10, as shown. The drawings 60 show the preferred construction. The actuating-levers are of skeleton form, each made of two steel rods bent to the desired shape and united laterally, their extreme ends turned inwardly to enter and form bearings for the tubular rollers 12 13. Each lever may be 65 cast of a single piece or may consist of a single rod, its middle portion forming the foot and the roller 12 being placed thereon before the rod is bent to form the lever. A metallic cross-piece 14 connects the spread rods transversely near the foot. They are also held in close contact by the fulcrum-plate 15, formed of heavy sheet metal folded tightly around the rods, its ends projecting each side of the tip of the fulcrum-post 6 or into a recess 70 therein and perforated to receive the rivet or bolt which connects the post and lever pivotally. For compactness in storage or transportation this connecting-pivot should be removable, so that the levers may be detached, 75 if desired. The leverage may be varied by varying the location of the fulcrum-plate.

The operation is as follows: The levers may stand about vertical, as in Fig. 3, and the mold or pan 7 containing material to be pressed is 80 placed on the base 5 and covered with plate 8. Then on spreading the lower arms 11 of the actuating-levers the tips of arms 10 or the rollers 13 thereon will bear downwardly on the top of said plate and exert a pressure proportionate to the weight of the press and material and to the relative length of the lever-arms, such pressure increasing automatically 85 as rollers 12 spread and the arms 11 become 90 more nearly horizontal.

100 I claim as my invention—

1. A pressing apparatus comprising a body or base to receive the material to be treated and a relatively movable cover for such material, in combination with actuating-levers 105 pivotally connected to the base, their long arms extending obliquely downward and outward, forming supports, and their short arms

bearing terminally on said cover, for the purpose set forth.

2. The described automatic press comprising a horizontal base or body with terminal 5 fulcrums, a mold or pan to receive the material and a loose-fitting cover therefor, in combination with actuating-levers, pivoted on said fulcrums, their long arms forming supporting-legs which extend downwardly and 10 obliquely outward and are provided with transverse rollers, while their short arms project inwardly and bear downwardly on the cover, for the purpose set forth.

3. The improved household-press, comprising a horizontal base or body with terminal 15 fulcrum-posts, a removable mold or pan to receive the material and adapted to rest on said

base, and a loose-fitting follower-plate in said pan, in combination with actuating-levers of skeleton form pivoted on said posts by suitable fulcrum-plates, the long arms of said levers extending downwardly and obliquely outward and broadened terminally to form transverse supporting-feet, and the short arms arranged to press with increasing force on the 25 follower-plate as said feet recede from each other and the base and pan descend somewhat, as set forth.

In testimony whereof I have affixed my signature in presence of two witnesses.

HENRY F. SHAW.
